CLAIM

The ornamental design for a container lid, as shown and described.

DESCRIPTION

FIG. 1 is a perspective view of a container lid embodying the new design;

FIG. 2 is a front view thereof, and the back view is a mirror image of the front view;

FIG. 3 is a left view thereof, and the right view is a mirror image of the left view;

FIG. 4 is a top view thereof; and,

FIG. 5 is a bottom view thereof.

The broken, dashed lines in the drawings are shown for illustrative purposes only and form no part of the claimed design.
